UNITED STATES PATENT OFFICE.

CHARLES D. ELLIOT, OF CAMBRIDGE, MASSACHUSETTS.

DESIGN FOR A PAPER COLLAR.

Specification forming part of Design No. 2,346, dated July 3, 1866.

To all whom it may concern:

Be it known that I, CHARLES D. ELLIOT, of the city of Cambridge, in the county of Middlesex and State of Massachusetts, have invented or produced a new and original Design for the Ornamentation of Paper Collars and Cuffs; and I do hereby declare that the following is a full and exact description of the same.

The design above mentioned consists of a line of ovals connected together at the ends of their longest axes, the upper and under side of each oval having a semicircular indentation, reference being had to the accompanying speci-

mens, upon which the ovals herein described are marked with the letters O O O.

What I claim as my invention, and desire to secure by Letters Patent, is—

The design consisting of a series of indented ovals connected together in a straight or curved line or lines, substantially as herein described and shown.

CHARLES D. ELLIOT.
